OTHER PUBLICATIONS

Exhibit C is a document entitled "User's Guide—Electric Breast Pump Kit" published by Gerber, the assignee of the present application, more than one year prior to the filing of the present application, and discloses a prior art electric breast pump.

Exhibit D is a photograph disclosing a prior art straight-walled funnel.

Exhibit E includes photographs of a non-operating foam model of a breast pump.

Exhibit F is a photograph of a funnel for a breast pump.

Exhibit A is a copy of packaging for the "Evenflo Soft-Touch Ultra" breast pump, published by Evenflo Products Company, Ravenna, Ohio, copyright 1988. The product is configured for use with a battery, but includes a DC V3 jack and is then adapted for use with an AC/DC transformer. An adapter is provided that includes a section to support a funnel, a section to threadingly engage a bottle, and an upper end configured to engage a suction port.

Exhibit B discloses photographs of the "Evenflo Soft-Tooth Ultra" breast pump manufactured by Evenflo Products Company, Ravenna, Ohio, which is the product shown in Exhibit A.

[57] CLAIM

The ornamental design for the electric breast pump, as shown and described.

DESCRIPTION

FIG. 1 is a front perspective view of the electric breast pump showing our new design;

FIG. 2 is a left side elevational view of the electric breast pump shown in FIG. 1, the right side being a mirror image of the left side;

FIG. 3 is a front elevational view of the electric breast pump shown in FIG. 1;

FIG. 4 is a rear elevational view of the electric breast pump shown in FIG. 1;

FIG. 5 is a top elevational view of the electric breast pump shown in FIG. 1; and,

FIG. 6 is a bottom elevational view of the electric breast pump shown in FIG. 1.

The broken line showing of the funnel and bottle in the FIGS. 1 through 6 is for illustrated purposes only and forms no part of the claimed design.
